UNITED STATES PATENT OFFICE.

JOHN BOYD RICKETTS, OF BALTIMORE, MARYLAND.

BACK-PRESSURE REDUCER.

No. 919,080.

Specification of Letters Patent.

Patented April 20, 1909.

Application filed December 30, 1908. Serial No. 470,085.

To all whom it may concern:

Be it known that I, JOHN BOYD RICKETTS, a citizen of the United States, and a resident of Baltimore city, in the county of Baltimore City and State of Maryland, have invented a new and Improved Back-Pressure Reducer, of which the following is a full, clear, and exact description.

The invention relates to blowers, pumps, stand pipes and like devices through which pass liquid or gaseous fluids, and its object is to provide a new and improved back pressure reducer for balancing the back pressure and thereby insuring easy running of the blower or pump and reduction of the wear of the blower and pump valves to a minimum, the reducer being for this purpose arranged with a revoluble air cell or float having tubular reaction arms through which passes the pumped fluid, to rotate the said chamber by the reaction of the fluid flowing out of the reaction arms.

A practical embodiment of the invention is represented in the accompanying drawings forming a part of this specification, in which similar characters of reference indicate corresponding parts in all the views.

Figure 1 is a side elevation of the improvement as applied to a stand pipe, parts being shown in section; Fig. 2 is a sectional plan view of the same on the line 2—2 of Fig. 1; Fig. 3 is a similar view of the same on the line 3—3 of Fig. 1; and Fig. 4 is a sectional side elevation of the improvement modified for use on the delivery pipe of a hydraulic ram.

The stand pipe A shown in Fig. 1 is provided with an enlargement or a casing B on which is mounted to turn on a ball bearing C a receiver D having an inlet E extending into the inlet of the casing B and the stand pipe A, to allow the water or other fluid flowing up the stand pipe A to enter the receiver D. On the top of the receiver D is bolted or otherwise secured an air cell or float F, and from the sides of the receiver D extend tubular reaction arms or pipes G, the fluid on flowing out of the arms G causing the receiver D and its float F to rotate in the direction of the arrow a' by the reacting force of the fluid on leaving the tubular arms G.

By providing the receiver D with an air cell or float F, the lifting action of the latter tends to relieve the ball bearing C of weight and thus allow free and easy running of the receiver D in the casing B. In order to pre-

vent the receiver D from being lifted off entirely from the ball bearing C the top of the said float F is engaged at the middle by a ball H held in a bracket I attached to the stand pipe section A' leading from the top of the casing B, so that the receiver D and its float are held against upward axial movement.

If desired, a second reducer similar to the one above described, may be attached to the stand pipe at the upper end of the section A', as shown in Fig. 1, and this reducer consists of a spherical casing B' in which rotates on a ball bearing C' a receiver D' having an inlet E' and a spherical float or air cell F' and tubular reaction arms G' discharging into the casing B' and causing the receiver D' to rotate within the casing B'. Upward axial movement of the receiver D' and the float F' is prevented by a ball H' engaging the top of the float F' and held in a bracket I' secured to the stand pipe section A' leading from the top of the casing B'.

In some cases it is desirable that the inlet E' for the receiver D' be provided internally with a spiral flange E' (see Fig. 4), which acts as a lift or pump on the fluid passing up through the inlet E' into the receiver D'. Otherwise, the receiver D' is the same as above described, and is provided with the reaction arms G' and an air cell or float F'.

Check valves are preferably placed in the upper delivery pipe or in the stand pipe, and a check valve is also placed in the stand pipe above the reducer to prevent downward leakage.

Although I have shown the reducer as applied to a stand pipe, it is evident the same may be used in place of the lifting valves in the discharge of the pump, and one or more such reducers may be used, one above the other, as indicated in Fig. 1 and above described. It can also be used for pumping liquids, air or gases, against pressure, in mines, refrigerating plants, gas works, city water supplies, gas wells, sailing and steam vessels, etc. and to increase the pressure in tanks.

Having thus described my invention, I claim as new and desire to secure by Letters Patent:

1. A back pressure reducer, comprising a casing having an outlet, a revoluble fluid receiver mounted to revolve in the said casing and having an inlet for the pumped fluid, and reaction arms extending from the said

receiver for the outflow of the fluid into the said casing and for rotating the receiver.

2. A back pressure reducer, comprising a casing having an inlet and an outlet, a revoluble fluid receiver within the said casing and having an inlet extending into the said casing inlet, and tubular reaction arms extending from the sides of the said revoluble fluid receiver and discharging into the said casing.

10 3. A back pressure reducer, comprising a casing having an inlet and an outlet, a revoluble fluid receiver within the said casing and having an inlet extending into the said casing inlet, a float on the said receiver, tubular

15 reaction arms extending from the sides of the said revoluble fluid receiver and discharging into the said casing, and means for holding the said receiver and its float against upward axial movement.

20 4. A back pressure reducer, comprising a casing, connected with the delivery of a pump, a fluid receiver mounted to turn within the said casing and having an inlet for receiving the pumped fluid, the said receiver being provided with an air cell and with tubular reaction arms opening into the said casing.

30 5. A back pressure reducer, comprising a casing, connected with the delivery of a pump, a fluid receiver mounted to turn within the said casing and having an inlet for receiving the pumped fluid, the said receiver being provided with an air cell and with tubular reaction arms opening into the said

35 casing, and a fixed arm carrying a ball engaging the said air cell to hold the same and the fluid receiver against axial upward movement.

6. In combination, a stand pipe, and a

back pressure reducer revolving therein, for counterbalancing the back pressure of the pumped fluid flowing through the said stand pipe, the said back pressure reducer having an air cell.

7. In combination, a stand pipe, and a plurality of back pressure reducers, each provided with an air cell and arranged in the said stand pipe one above the other, each back pressure reducer having a revoluble chamber into which passes the pumped fluid, and tubular reaction arms for discharging the fluid from the chamber and causing the latter to turn.

8. A back pressure reducer comprising a casing having an outlet, a revoluble fluid receiver within the said casing and having an inlet connected with a fluid supply, a spiral flange in the said inlet, and reaction arms extending from the said receiver for the outflow of the fluid into the said casing and for rotating the receiver.

9. A back pressure reducer comprising a casing having an outlet, a revoluble fluid receiver within the said casing and having an inlet connected with a fluid supply, a spiral flange in the said inlet, reaction arms extending from the said receiver for the outflow of the fluid into the said casing and for rotating the receiver, and an air cell for the said receiver.

In testimony whereof I have signed my name to this specification in the presence of two subscribing witnesses.

JOHN BOYD RICKETTS.
